INVENTOR:

Paul Stahl.

UNITED STATES PATENT OFFICE.

KARL STAHL, OF FRIEDRICHSHAFEN, GERMANY, ASSIGNOR TO THE FIRM LUFT-SCHIFFBAU ZEPPELIN GESELLSCHAFT MIT BESCHRÄNKTER HAFTUNG, OF FRIEDRICHSHAFEN, GERMANY.

RELEASING DEVICE.

Application filed June 28, 1920. Serial No. 392,607.

To all whom it may concern:

Be it known that I, KARL STAHL, a citizen of Germany, residing at Friedrichshafen, Germany, have invented certain new and 5 useful Improvements in Releasing Devices (for which I have filed application in Germany September 19, 1917), of which the following is a specification.

My invention relates to releasing devices 10 especially for use in connection with aerial vehicles.

As is well known, all bodies, such as bombs or ballast, which are designed to be thrown off from aircraft, must be kept perfectly safe in a closed space, whilst, on the other hand they must be instantly discharged, if necessary, in order to obtain the desired result.

The releasing device according to the 20 present invention complies with all these requirements and is simple in construction, can easily be mounted, requires very little space and is perfectly reliable in operation.

The device according to the present invention is provided with a casing having two slits arranged in different planes preferably vertically disposed with relation to one another. In one of these slits an oscillating lever is movably disposed which, 30 is capable of crossing the other slit with an arm of sector-shaft. Both the external and internal surfaces of the arm, which is provided near the axis of rotation of the lever, extend at least approximately concentrically 35 to the said axis, the external surface moving in corresponding abutments of the casing, whilst the internal surface serves for the reception of the load.

In order to render the manufacture and 40 the mounting of the device especially simple, I prefer providing a casing consisting of two slotted plates, which are disposed at a certain distance from each other so as to embrace the oscillating lever and are 45 rigidly connected with each other, an abutment for the sector-shaped arm being further provided.

In the accompanying drawing a diagrammatic view of a device embodying my invention is illustrated.

Fig. 1 being a lateral view of the device and Fig. 2 a vertical section on line 2—2 in Fig. 1.

Two plates A, bent in their upper por-

tions a^1 and each provided in their lower portions with a vertical slit a^2 , are riveted together at the bent surfaces, so as to form clamps, which are open at their ends. Within the space thus formed, the upper end B^1 of a lever B, the axis of rotation of which is secured below the bent portion a^1 , but above the vertical slits a^2 , is free to oscillate. The end B^1 of the lever is provided with an arm b^2 of sector-shape, which, in the locked position shown, forms a bridge 55 across the central part of the cross-slit produced by the openings a^2 . The internal surface b^3 of the lever arm b^2 serves for the reception of a hook C. The external surface b^4 of the lever-arm, which lies concentrically to the internal surface b^3 and to the axis of rotation of the lever, rests with its ends against two abutments D^1 , 60 D^2 , provided between the plates A. These abutments, together with a third abutment D^3 , serve as spacers for the plates A. The abutments D^2 , D^3 act as stops for the end 65 positions of the lever, which in its part B outside the casing A essentially consists of a tube.

In the device shown in the drawings, the release is securely fixed between two rails provided in the frame of an aircraft. Where such rails are not at disposal, the device may be fixed by means of an eye a^3 and some 70 ropes G between the said eye and the frame, so that it is free to oscillate, since it is practically of no importance whether the oscillating axis of the swinging load is arranged in the upper part of a stationary 75 cross-slit a^2 , or whether the device as a whole oscillates around the point of attack of the rope ties. For the quick disengagement of the swinging lever, an oscillating suspension 80 of the complete device offers no difficulty, since the device does not materially change its position under the action of the weight, if the oscillating lever is moved in the sense of the release.

If the internal surface b^3 of the lever arm b^2 is arranged perfectly concentrically to the axis of rotation of lever B, the suspension 100 of the load takes place with indifferent equilibrium. To ensure a greater safety if, for the purpose of a quick release, the splint 105 E should be removed, a safe arrangement of parts can be provided by bending the internal surface b^3 of the lever-arm b^2 to-

wards its free end. If the lever B is to be released, the load must be slightly lifted corresponding to the increased curvature of the surface b^3 , before the lever-arm b^2 leaves 5 the cross-slit a^2 and releases the hook C.

Claims:

1. In a device of the kind described in combination, a narrow casing open on one side, a rocking lever pivoted to the upper 10 part of said casing and extending outwards through the open side thereof, an arm on said lever extending substantially at right angles therefrom through part of said casing, and indentures in the casing walls ex- 15 tending in parallel from the bottom upwards, said arm crossing said indentures at a distance from their upper ends, so as to serve as a support for the load.

2. In a device of the kind described in 20 combination, a narrow casing open on one side, a rocking lever pivoted to the upper part of said casing and extending outwards through the open side thereof, an arm on said lever extending substantially at right 25 angles therefrom through part of said casing substantially concentrically to the pivot of said lever, and indentures in the casing walls extending in parallel from the bottom upwards, said arm crossing said indentures 30 at a distance from their upper ends so as to serve as a support for the load.

3. In a device of the kind described in combination, a narrow casing, open on one side, a rocking lever pivoted to the upper part of said casing and extending outwards 35 through the open side thereof, an arm on said lever extending substantially at right angles therefrom through part of said casing, indentures in the casing walls extending in parallel from the bottom upwards, said 40 arm crossing said indentures at a distance from their upper ends so as to serve as a support for the load, and an abutment in said casing for the outer edge of said arm.

4. In a device of the kind described in 45 combination, two sheet metal walls spaced apart and fixed to one another so as to form a casing, a rocking lever pivoted to the upper part of said casing and extending outwards through the open side thereof, an arm 50 on said lever extending substantially at right angles therefrom through part of said casing, and indentures in the casing walls extending in parallel from the bottom upwards, said arm crossing said indentures at a 55 distance from their upper ends so as to serve as a support for the load.

In testimony whereof I affix my signature.

KARL STAHL.
